(57) **CLAIM**

The ornamental design for a wall light, as shown and described.

DESCRIPTION

FIG. 1 is a front and left perspective view of a wall light, showing my design.

FIG. 2 is back and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown on the drawings depict portions of the wall light that form no part of the claimed design.
